UNITED STATES PATENT OFFICE.

AUGUST J. HARTFIELD, OF LOS ANGELES, CALIFORNIA.

HEATER.

Application filed January 16, 1928. Serial No. 247,079.

This invention relates to a radiant heater which embodies improved means for heating the air of a room, hall, etc.

An important object is to provide a more cheaply manufactured sheet iron construction of the furnace wall so arranged to co-operate with the upper ends of the radiants as to removably support the latter in an efficient manner.

10 A further object is to simplify and cheapen the interior construction of a heater by the provision of a novel metal member which is adapted both to support the heating elements and to form portions of the 15 walls of the heater casing.

Other objects and advantages may hereinafter appear.

Referring to the accompanying drawings which illustrate a preferred embodiment of 20 the invention.

Figure 1 is a front view of a portable heater embodying the invention.

Figure 2 is a vertical section on line 2—2 of Figure 1.

25 Figure 3 is a horizontal section on line 3—3 of Figure 1.

Referring in detail to the drawings, the upright casing 5 is provided with an open face 6 just behind which is located the upright heating elements 7. Said heating elements are heated by a series of burner elements 8 of any desired construction located therebeneath, as well shown in Figure 2, the lower portion of the casing being provided 35 with a burner chamber 9 having a front wall 10 provided with cold air intakes 11 and 11^a at its front and bottom sides respectively. At the top of the casing is provided a heated air chamber 12, there being located between said chambers 9 and 12 a jacket 13 which partially encloses the series 40 of heating elements 7 and which has a rear wall 14 in spaced relation to the back wall 15 of the furnace casing, thereby forming an upright flue 16, and side flues 16^a which lead from the burner chamber 9 to the top chamber 12.

Referring in detail to the construction of the jacket 13, said jacket by preference and as shown, consists of an upward prolongation of the sheet metal wall 10 of the heater casing, said wall 10 having a rearward extension 18 adjacent thereto. The part 18 at its rear edge joins the rear wall 14 of said 50 jacket. The top of the jacket has a forwardly directed portion 19 which terminates

in a channelled flange 20 that is fitted over the upwardly extending top flanges 21 of the heating elements 7.

Each of the heating elements 7 is provided with a top wall 22 which is inclined downwardly and rearwardly in spaced relation to the top wall 19 of the jacket 13, and the aforementioned back wall 14 of said jacket is spaced rearwardly of the heating 65 elements 7, thus providing a heat radiating chamber 23 between said heating elements and said wall 14.

The top chamber 12 of the heater is provided in its top wall 12^a with an upwardly 70 and forwardly directed apertured portion 24 to direct the air forwardly and upwardly into the room, it being understood that the furnace will usually be placed with its back 15 near one of the walls of the room. 75

The bottom 10^a of the heater is shown formed as a rearward continuation of the front wall 10 and with air intake openings 11^a passing therethrough. Said bottom is shown having a flange 10^b for attachment to 80 the back of the furnace by means of rivets 10^c. The member which forms the top and back of the furnace may consist either of cast iron or of sheet iron. Sheet metal members 11 and 14 may support the cross wall 85 18 which supports the heating elements 7. Cross wall 18 is formed of a separate piece of metal in order to provide for expansion and contraction thereof, independently of the adjacent members of the heater. 90

In operation, heated air is radiated horizontally into the room from the upright heating elements 7 located at the front side of the heater and forming the front wall of the chamber 23; while at the same time upwardly and forwardly directed currents of heated air are escaping into the room through the apertured top portion 24 which is located above the heating elements 7. Owing to the currents of heated air being delivered into the room from these two sources and in two general directions as has been explained, there is created within the room an efficient circulation of heated air by passing air through intakes 11 and 11^a into chamber 9, thence through the flues 16 and 16^a into chamber 12, and through said apertured portion 24 as indicated in the annexed drawing. 100

I claim:—

105 In a radiant heater, an upright casing having a front wall which is provided with

a downwardly directed lip which forms the upper margin of the opening for the heater proper, a heating element within said casing and having an upright flange at its top, a sheet metal jacket for said heating element said jacket having a top wall with a channel portion which fits around the rear, top

and front of said upright flange and which abuts against the inner surface of said lip of the casing, said channel portion consisting of angular bends of the sheet metal in which it is located. ¹⁰

In testimony whereof I affix my signature.

AUGUST J. HARTFIELD.
